CLAIM

The ornamental design for a swimming pool cleaner part, as shown and described.

DESCRIPTION

FIG. 1 is a first perspective view of a swimming pool cleaner part, showing my new design;

FIG. 2 is a second perspective view thereof;

FIG. 3 is a front elevational view thereof;

FIG. 4 is a left side view thereof;

FIG. 5 is a right side view thereof;

FIG. 6 is a top plan view thereof; and,

FIG. 7 is a bottom plan view thereof.

(Continued)

The broken lines shown in the drawings depict portions of the swimming pool cleaner part that form no part of the claimed design.
